(57) **CLAIM**

The ornamental design for a suspended ceiling grid tee, as shown and described.

DESCRIPTION

FIG. 1 is an isometric view of a suspended ceiling grid tee showing our new design;

FIG. 2 is an end view thereof;

FIG. 3 is a right side view thereof, the left side view being a mirror image of this view;

FIG. 4 is a top plan view thereof; and,

FIG. 5 is a bottom plan view thereof.

The dotted-line showing in the drawings illustrates environmental matter and forms no part of the claimed design.
